HENRY H. COVERT, OF NEW YORK, N. Y.

Letters Patent No. 96,398, dated November 2, 1869.

IMPROVED HATCHWAY-GUARD.

The Schedule referred to in these Letters Patent and making part of the same.

To all whom it may concern:

Be it known that J, HENRY H. COVERT, of New York, in the county of New York, and State of New York, have invented a new and improved Hatchway-Guard; and I do hereby declare that the following is a full, clear, and exact description thereof, which will enable others skilled in the art to make and use the same, reference being had to the accompanying drawings, forming a part of this specification.

This invention relates to improvements in guards for hatchways in buildings; and has for its object to provide a removable safety-guard, for the prevention of accidents to persons by inadvertently stepping over the edges of the openings in the floors and falling through.

The invention comprises a hinged fence or railing for each side perpendicular to the wall, hinged to it, and adapted for raising up against the wall when freight is to be raised or lowered.

Also, an arrangement of spring-guard for the side, parallel with the wall, made capable of moving up and down in guides below the floor, and provided with springs for throwing them up, and held down by catches arranged to be detached by the weight of a person on the floor, approaching the hatchway, the floor near the same being hinged and movable.

Figure 1 represents a sectional elevation of my improved guard, the section being taken on a plane perpendicular to the wall of the building, alongside of which the hatchway is placed;

Figure 2 represents a sectional elevation of the same, taken on the line $z z$ of fig. 1; and

Figure 3 represents a partial plan view.

A represents the wall of the building, by the side of which the hatchway is arranged, and B represents the floor line.

C is the usual trap door, employed to close the opening when not required for use.

E and F are the side railings, showing two different ways of constructing them.

G represents the front spring-rails or guards.

The side rails may be composed of one bar E, connected to the wall, two bars, E², pivoted to it, one on each side, and one above the other, and a post, E³, pivoted to the other ends of the bars E², so as to fold up against the wall, where it may be secured by hooks E⁴ when access to the hatchway is desired, or to be turned down to guard the same, as represented in fig. 1, the post E³ being tenoned to enter a mortise in the floor, as shown at E⁵.

Or the said side rails may be made as shown at F, where the posts F¹ and F² are slotted, for the introduction of a central rail, F³, two other rails, F⁴, being arranged similarly to the rails E².

The central rail F³ is arranged to be about midway between the rails F⁴ when adjusted to guard the hatchway. These bars may be arranged to fold into recesses in the wall, so as to be flush with the same, as represented at J.

For the side fronting the wall, I arrange a vertically-sliding guard of two or more sections, telescoped, or arranged to slide upon each other. This said guard is composed of horizontal rails H H¹ H², having vertical extensions at each end, by which the connections are formed for sliding on each other; these may be arranged as preferred. I have arranged the two outside projections with grooves, and the inner one with tongues fitting the grooves.

The said outside projections are also provided with stop-pins, I, for remitting the movement on the central one, which stops come against shoulders of recesses formed in the tongues of the central projection, as shown at K.

I represents springs, arranged under the projection of these rails, at each end, to force them up.

M are S-shaped spring-dogs, for holding them down. They are pivoted at N, and provided with round projections at the upper ends, to take into holes O in the upper bar H when pressed down, and they are held in this position by spring P; the lower ends are shouldered at Q, and projections R from a hinged part, T, of the floor, rest on the said shoulders, so that when a person approaching the hatchway steps upon the hinged part T and presses it down, the dogs will be thrown back out of the holes in the top rail, and the springs will throw the rails up between the person and the hatchway.

When freight is to be passed over the hinged part, skids may be so arranged above it as not to press it down to disengage the dogs.

These spring-rails may also be arranged on the other sides of the hatchway, in place of the folding bars E and F, if preferred; and in some cases I propose so to arrange them.

The posts E³ and F³ may be provided with spring-catches V, for holding the rails H up.

Having thus described my invention,

I claim as new, and desire to secure by Letters Patent—

1. The folding hatchway-guard E or F, arranged in combination with the floor and wall, for adjustment in front of the hatchway, or for folding up against the wall, substantially as specified.

2. The combination of the vertically-sliding spring-rails H H¹ H², hinged floor T; and dogs M, when arranged in the floors for guarding the hatchway, substantially as specified.

3. The combination, with the folding rails E or F, of the vertically-sliding spring-rails H H¹ H², substantially as specified.

The above specification of my invention signed by me, this 9th day of August, 1869.

HENRY H. COVERT.
